(57) **CLAIM**

The ornamental design for a bottle, as shown and described.

DESCRIPTION

FIG. 1 is a top, front, right perspective view of a bottle showing our new design;

FIG. 2 is a front view thereof, wherein the rear view is a

mirror image of FIG. 2;

FIG. 3 is a right side view thereof, wherein the left side view

is a mirror image of FIG. 3; and,

FIG. 4 is a top view thereof.

The broken lines immediately adjacent to the shaded area define the bounds of the claimed design and form no part thereof. The broken lines depicting the remainder of the bottle show features that form no part of the claimed design.
